UNITED STATES PATENT OFFICE.

AP TREVOR JONES, OF CHICAGO, ILLINOIS, ASSIGNOR TO AMERICAN STEEL
FOUNDRIES, OF CHICAGO, ILLINOIS, A CORPORATION OF NEW JERSEY.

ANCHOR.

1,873,740.

Specification of Letters Patent.

Patented Apr. 5, 1921.

Application filed May 1, 1920. Serial No. 378,030.

To all whom it may concern:

Be it known that I, AP TREVOR JONES, a citizen of the United States, residing at Chicago, in the county of Cook and State of Illinois, have invented certain new and useful improvements in Anchors, of which the following is a specification.

This invention relates to anchors.

Generally speaking, there are two types of anchors, one known as the stock anchor, in which the shank of the anchor has no relative movement with respect to its crown or head, and the other one known as the stockless anchor, in which the shank has a relative movement with respect to its crown or head. It is to the latter type of anchor that my invention has particular application.

The main advantages of the stockless type of anchor over the other type are the ease of stowing away the anchor on the ship, and primarily in that the stockless type of anchor has two flukes for simultaneously engaging and hooking into the bottom of the sea for holding firmly.

The one disadvantage of the stockless anchor is that the flukes thereof are a little slow in hooking into the bottom of the sea after reaching same.

Accordingly, one object of this invention is to overcome this disadvantageous feature in a simple and efficient manner.

Another object is to provide a stockless anchor adapted to meet all the requirements for successful use.

These and other objects are accomplished by means of the arrangement disclosed on the accompanying sheet of drawings, in which—

Figure 1 is a front elevation of an anchor embodying my invention;

Fig. 2 is a side elevation of the same anchor;

Fig. 3 is a fragmentary side elevation of the same anchor, a portion of the head being in section, and showing the shank in vertical position, with the flukes at an angle of 45° with respect thereto, one of the two positions taken by the parts of the anchor as the anchor is being lowered and raised; and,

Fig. 4 is a side elevation of the same anchor, a portion of the head being shown in section, and showing the shank locked to the head of the anchor for causing a quick gripping action of the anchor when passed into

engagement with the bottom of the sea, the position shown being that which is assumed after the head of the anchor has reached the bottom of the sea and the shank having moved downwardly a certain predetermined amount from its vertical position.

The various novel features of the invention will be apparent from the following description and drawings and will be particularly pointed out in the appended claims.

Referring to the figures of the drawings, it will be noted that I have shown a stockless type of anchor including a head 10 and a shank 11, the latter being pivotally connected to the former by means of trunnions 12 extending laterally from the shank and coöperating with bearing portions within the head. The inclined walls 13 of the head form stops for limiting the relative movement between the shank 11 and head 10. Preferably the maximum relative movement between said parts is about 90°, there being a 45° swinging movement to either side of a central aligned position of the head and shank. The head 10 is provided with two flukes 14 which are the ground engaging or gripping members. The head is also provided with oppositely and laterally extending projections 15 at the base of the flukes to cause the flukes to assume a digging or gripping position when the head of the anchor rests upon the bottom of the sea, as shown in Fig. 4. However, as mentioned hereinabove, the stockless type of anchor is a little slow in digging into and gripping the bottom of the sea in spite of the inclination given to the flukes by the projections 15, as shown in Fig. 4. To overcome this disadvantageous feature and to cause a quicker gripping action of the flukes of the anchor, I have provided means whereby the shank of the anchor will become locked with respect to the head thereof at the proper point so that the weight of the shank, together with the weight of at least a portion of the chain, will act in a manner to increase the digging or gripping action of the flukes of the anchor.

As shown in Fig. 4 of the drawings, the shank 11 of the anchor is locked to the head 10 thereof by one of the two locking members 16 having a hooked portion 17 which is in locking engagement with a shoulder 18 formed on the head of the anchor. The locking members 16 are pivotally connected

on opposite sides of the shank 11 on a pin 19 extending through the shank and through the members 16. Each of said locking members 16 is provided with a weighted portion 5 20 for holding the hooked portion 17 in a position to hook over and remain in hooked relationship with said shoulder 18 as the shank swings downwardly from the vertical position to the position shown in Fig. 4, and 10 also for permitting the hooked member 16 to move out of locking engagement with the shoulder of the head when the shank 18 is moved toward a vertical position from that shown in Fig. 4. With the parts as shown 15 in Fig. 4, the shank 11 is prevented from moving downwardly relatively to the head of the anchor, and accordingly, the weight of the shank and also the weight of the chain 21, or at least a portion thereof and its 20 clevis member 22 connecting it to the shank 11, act in a manner to cause a relatively quick gripping and hooking action of the flukes into the bottom of the sea, this being especially true in view of the fact that the 25 weight of the shank 11, clevis 22 and chain 21 act through a relatively long lever arm. It will be understood that the shank 11 may be locked to the other side of the head by the associated gravity actuated hook member 16 30 in a manner similar to that shown in Fig. 4 of the drawings.

It is my intention to cover all modifications falling within the spirit and scope of the following claims.

35 I claim:

1. A stockless anchor including a head, a shank movably connected thereto, and means for locking said head and shank in a given relative position for creating a gripping leverage causing a quick gripping action of the anchor.

2. A stockless anchor including a head, a shank movably connected thereto, and means for automatically locking said head and shank in a given relative position for creating a gripping leverage causing a quick gripping action of the anchor.

3. A stockless anchor including a head, a shank movably connected thereto, and gravity actuated means for locking said head and shank in a given relative position for causing a quick gripping action of the anchor.

4. A stockless anchor including a head, a shank movably connected thereto, and means carried by the shank for locking said head and shank in a given relative position for creating a gripping leverage causing a quick gripping action of the anchor.

5. A stockless anchor including a head, a shank movably connected thereto, and mem-

bers mounted on opposite sides of the shank for locking said head and shank in a given relative position for creating a gripping leverage causing a quick gripping action of the anchor.

65

6. A stockless anchor including a head, a shank movably connected thereto, and oppositely extending members for engaging opposite portions of the head in given relative positions for creating a gripping leverage 70 causing a quick gripping action of the anchor.

70

7. A stockless anchor including a head, a shank movably connected thereto, means for locking said head and shank when they are 75 in certain relative positions for creating a gripping leverage causing a quick gripping action of the anchor, and means for unlocking said head and shank.

75

8. A stockless anchor including a head, a shank movably connected thereto, means for automatically locking said head and shank when they are in certain relative positions for creating a gripping leverage causing a quick gripping action of the anchor, and 85 means for automatically unlocking said head and shank.

85

9. A stockless anchor including a head having flukes, a shank pivotally connected to said head, and means for locking said 90 head and shank when the flukes have assumed a substantially horizontal position for creating a gripping leverage causing a quick gripping action of said flukes.

90

10. A stockless anchor including a head, 95 a shank pivotally connected thereto, and means for locking said head and shank in a given relative position when the shank has moved from a vertical position a predetermined amount.

100

11. A stockless anchor including a head, a shank pivotally connected thereto, and means for locking said head and shank in a given relative position when the shank has moved from a vertical position a predetermined amount and for unlocking said head and shank when the shank has moved toward a vertical position from a locking position.

105

12. An anchor including a head having a shoulder portion, a shank pivotally connected to said head, and a pivotally mounted hook carried by said shank for engaging said shoulder for locking the head and shank in a given relative position for causing a 115 quick gripping action of the anchor.

115

Signed at Chicago, Illinois, this 24th day of April, 1920.

AP TREVOR JONES.
